GEORGE L. BLANCHARD, OF CALEXICO, CALIFORNIA

METHOD AND APPARATUS FOR DEFIBRATING COTTONSEED HULLS

Application filed February 19, 1930. Serial No. 429,541.

This invention relates to a method and apparatus which is particularly of value in defibrating cottonseed hulls.

In my copending application Serial No. 358,998, filed April 29, 1929, there is described a method and apparatus for defibrating cottonseed hulls in which a hammer mill is employed. The hammer mill is caused to whirl and scrape the hull or the skin of the hulls against a screen which is sufficiently fine to permit only the fibers and powder of the hull to escape while air current is drawn through the screen.

It is the general object of this invention to provide a process and apparatus for defibrating cottonseed hulls which will produce a cleaner product than those generally employed and which will possess a greater capacity and in which the fiber screen will possess a longer life.

I have found that when cottonseed hulls are defibered by stripping the fibers from the hulls by hammer blades that a cleaner separation of the fiber from the hulls is attained by causing the fiber to be drawn upwardly and away from the hammer mill in reaching the fiber screen rather than the older practice of having the hammer blades scrape the hulls against the fiber screen.

It is further found that by providing a beater chamber or zone in which the hulls are beat against a screen that a substantial part of the defibered hulls may be discharged from the machine separate from the fiber.

The present invention includes in general principles a process and apparatus in which there are three different zones of operation upon the cottonseed hulls. There is first a hull brand screening zone in which the hulls are beaten and those hulls which are free from fibers permitted to escape from the apparatus; then there is a hull screening zone in which the hulls carrying fiber are scraped by hammer blades. The third element consists of a fiber screening zone separate from the fiber scraping zone and which is arranged so that mainly fibers only are drawn into the screening zone, the heavier hull particles being passed back to the hull beating or to the hull scraping zones.

By provision of these three separate elements and the provision for an automatic selection of the proper material to pass from each to the other, I have found that a product is produced containing less dirt and thrash, and moreover the process and apparatus has a greater capacity.

Various further objects and advantages of the present invention will appear from the description of a preferred form of the process and apparatus embodying the invention. For this purpose there has been hereafter described a preferred form or example of a process and apparatus embodying the invention. The description is given in connection with the accompanying drawings, in which, Figure 1 is an elevation partially in section. Figure 2 is an elevation at right angles to Figure 1.

Figure 3 is a fragmentary section on the irregular line 3—3 of Figure 1.

Referring to the drawings, the apparatus is illustrated as comprising an inlet 2 by means of which cottonseed hulls can be fed to the apparatus. The inlet 2 enters a hull brand discharge chamber 3 which includes a rotary beater 4 which may be driven by any suitable means, not shown, and is provided with a number of radially extending paddle members 5. The beater 4 is in operation rotated clockwise, as viewed in Figure 1, and beats the hulls against a hull screen 6 which permits any hull skins that are free, or fiber, to escape without passing on to the remainder of the apparatus. Those hull skins which have fibers adhering thereto are prevented by an air current from passing out the hull screen. The hull screen has comparatively coarse outlets and there is a baffle 7 which operates as a guard to direct the ejected hull particles from the screen 6 downward. The hull brand discharge chamber 3 is closed at the upper end near the inlet 3 by a concave baffle 8 which prevents the beater 4 from ejecting the hulls upwardly into the chamber 9, which is a separation chamber.

The hull chamber has an opening communicating with a fiber scraping chamber 10. The fiber scraping chamber 10 is defined by a lower concave wall 11 and a roughened block 12.

against which the hulls are scraped by a hammer mill member 13.

The hammer mill member 13 is composed of a steel cylinder 16 formed of discs 17 and rods 18. On the rods 18 are pivoted hammer blades or cutters 19 of thin metal, the planes of which cutters 19 lie perpendicular to the axis of the mill member. Sufficient of the blades are pivoted on the rods 18 to together 10 cover most of the area of the cylinder. The blades 17 operate as hull scraping members and to facilitate this action are preferably serrated at their edges, as indicated at 20, and each blade is provided with two openings 21 15 by means of which they may be pivoted on the rods 18. By providing two openings the blades may be reversed and their opposite edges used in hull severing operations when one of their edges becomes dull. The front 20 edges of the blades 19 are serrated back farther than the rear edges so as to permit all of the serrations to be brought into effective operation. The hammer mill member 13 is mounted on bearings outside of the scraping 25 chamber 10 and is there driven by any suitable means (not shown) preferably in a counter-clockwise manner, as viewed in Figure 1, or in such direction as to first eject the material from the hull chamber 3 upwardly into the 30 separation chamber 9.

The separation chamber 9 is an enlarged chamber which provides sufficient space to permit a rising stream of air to separate and draw upwardly any free fibers or fibers which 35 are substantially free from hull skin while permitting heavier incompletely separated particles of hull and fiber to fall downwardly upon the hammer mill member and to be thereby carried around with the same into the 40 fiber scraping chamber 10. The top of the separation chamber 9 is provided with a semi-cylindrical fiber screen 22 having relatively fine openings just sufficient in size to permit the escape of separated fibers but to prevent 45 the escape of incompletely separated fibers. For example, suitable size of screen openings is approximately $\frac{1}{2}$ inch in size. Revolvable under and in close proximity to the fiber screen 22 is a beater 23 with the radial paddle 50 arms 24 which takes fibers drawn upwardly and beats the same against the screen 22.

The screen 22 is surrounded by a hood 25 terminating in a discharge opening 26 to which in operation is attached a line leading 55 to a suction fan for creating the current of air utilized in the process and apparatus. There is provided in the hood 25 one or more dampers 27 of which two are shown, which may be open to control the draft within the 60 apparatus.

There is also provided near the lower end of the separation chamber, one or more openings covered by a damper 28 for further regulation of the air currents within the apparatus.

In the operation of the apparatus thus described and in the process of the present invention, fiber hulls are fed continuously or intermittently into the opening 2. Here the hulls first contact with the beater 4 in the hull brand discharge chamber 3 and are directed by the beater against the hull screen 6. This permits at the start of the process and operation, the dust and fine thrash present in the hulls to pass out of the process and apparatus and also allows any hull skins that have no fiber on them to escape.

The suction imposed on the opening 26 draws air through the screen 6 and prevents any hull skin bearing fiber from passing out of the screen 6. From the chamber 3 the hull skins pass under the baffle 8 and are thrown to the side wall 29 of the separation chamber 9 where the force of the hammer member 15 and the uprising current of air in the separation chamber 9 starts a whirl of material upwardly in a manner as indicated by the arrows in the figure.

Since the hull brand has less resistance to the suction of air than separated fibers, it is not drawn up into contact with the fiber beater but is in place carried around by the hammer member 15 and scraped by the hammer blades 21 free of its fiber against the roughened block 12 and concave wall 11 and the hulls denuded of fiber, and then discharged into the hull chamber 3. The roughened block 12 operates to restrain or slow down the speed at which the hull particles pass through the hull scraping chamber and is thus effective in increasing the efficiency of the scraping operations.

In the hull discharge chamber 3 the de-fibered hulls are again thrown against the screen 6 and are this time discharged from the screen. The fibers which are scraped from the hulls or hull skins in this operation are drawn upwardly, as the hulls leave the hammer mill, into the separation chamber, and finally come into contact with the fiber beater 23 which ejects the same through the fiber screen 22 and out through the opening 26.

By the process and apparatus herein described the delinted hulls are prevented from being whirled back into the hull scraping zone and accordingly, the capacity of the apparatus is increased. The separation of the fiber which is scraped by the hulls and is discharged from the process and apparatus from the fiber beater and screen which is placed upwardly and away from the hammer mill, is found to accomplish a cleaner separation and to prevent the inclusion in the produced fibers of a considerable amount of powdered hulls.

While the particular form or example of the process and apparatus embodying this invention herein illustrated is well adapted to carry out the objects of the present invention, it is to be understood that various modifications and changes may be made without departing from the principles of the inven- 130

tion, and the invention includes all such modifications and changes as come within the scope of the appended claims.

I claim:

5. 1. A process of defibrating cottonseed hulls which comprises, first passing the hulls to a hull beating zone, therein beating the hulls while discharging delinted hulls, therefrom passing the incompletely delinted hulls and substantially hull-free fibers into a separation zone, therein separating by an uprising current of air the substantially hull-free fibers from incompletely delinted hulls, and passing the incompletely delinted hulls to an independent hull scraping zone, scraping the fibers from the hulls in said zone, and ejecting the hulls back into the hull beating and discharge zone, and passing the fibers separately from the scraping zone to said separation chamber.
10. 2. A system of defibrating cottonseed hulls which comprises, first beating the hulls against a delinted hull discharge screen simultaneously passing a current of air through the screen sufficient to prevent fibers and fiber bearing hulls from being discharged, then passing the hulls to a separate fiber scraping zone wherein the hulls are scraped of fiber, and passing a current of air through the fiber scraping zone of sufficient velocity to draw the separated fibers upwardly from the fiber scraping zone, said latter current of air being insufficient in velocity to carry therewith the heavier delinted hulls, and passing the heavier delinted hulls from the fibrous scraping zone into the hull discharging zone.
15. 3. A process of defibrating hulls which comprises, first passing the hulls to a delinted hull screening zone, therein beating the hulls against the screen, then passing the hulls to a separation chamber, therein subjecting the hulls to a rising air current sufficient to carry upwardly the separated fibers but insufficient to draw upwardly the hulls, passing the hulls to a fiber scraping zone and therein scraping the hulls to liberate the fiber therefrom, and then subjecting the scraped hulls from the fiber scraping zone to further beating, while passing an air current from the hulls being beaten to said separation zone so that the separated fibers are drawn into said separation zone.
20. 4. An apparatus for delinting fiber from cottonseed hulls comprising, a roller having hammer blades operative for scraping fibers from the hulls, a separate hull beater chamber adapted to discharge and receive hulls to and from the hammer blades, a delinted hull screen in said hull beater chamber, a fiber screen receiving fibers from the hammer blades, means for drawing air through the delinted hull discharge screen and out of the fiber screen, and means for introducing the hulls first into the hull beater chamber.

5. An apparatus for delinting fiber from cottonseed hulls comprising, a fiber scraping chamber, a rotor having hammer blades operative within said chamber, a supplemental hull beater chamber having a hull discharge screen and a rotary beater therein, said supplemental chamber communicating with the fiber scraping chamber, and a fiber screen disposed above and distantly spaced from said rotary beater, and a fiber beater disposed under said screen.

6. An apparatus for delinting fiber from cotton seed hulls comprising, a fiber scraping chamber, a rotor having hammer blades operative within said chamber, a supplemental hull beater chamber having a hull discharge screen and a rotary beater therein, said supplemental chamber communicating with the fiber scraping chamber, a fiber screen disposed above and distantly spaced from said rotary beater, a fiber beater disposed under said screen, and means for creating draft air through the fiber screen for carrying fibers therethrough.

7. An apparatus for delinting cottonseed hulls comprising, a main chamber, the lower part of which is closed by substantially semi-cylindrical walls, a rotor having hammer blades located close to said walls, the chamber providing a large open separation zone above the rotor, a fiber screen at the top of said chamber, means for drawing air upwardly through said chamber, and a rotary fiber beater disposed close to the fiber screen.

8. An apparatus for delinting fiber from cottonseed hulls comprising, a hull beater chamber having a hull discharge screen, a hammer mill chamber including a hammer mill roller, a hammer mill chamber and hull beater chamber communicating and a hammer mill member and beater revolving in opposite directions, a separation chamber above said hammer mill chamber, and a fiber screen and beater at the top of said separation chamber.

Signed at Los Angeles, California this 10th day of February 1930.
